UNITED STATES PATENT OFFICE.

JOHN R. MEADOWCROFT, OF MONTREAL, QUEBEC, CANADA.

ALARM-ACTUATING APPARATUS.

1,338,147.

Specification of Letters Patent. Patented Apr. 27, 1920.

Application filed September 17, 1917, Serial No. 191,809. Renewed October 13, 1919. Serial No. 330,526.

To all whom it may concern:

Be it known that I, JOHN ROBERT MEADOWCROFT, a subject of the King of Great Britain, and resident of the city of Montreal, in the Province of Quebec, Dominion of Canada, have invented certain new and useful Improvements in Alarm-Actuating Apparatus; and I do hereby declare that the following is a full, clear, and exact description thereof.

My invention relates particularly to the retarding apparatus of automatic fire extinguishing and alarm systems of the type comprising a supply of water under pressure, the retarding and alarm apparatus, a heat-actuated sprinkler system, pipe systems whereby this apparatus supplies the sprinkler systems, and means actuated by the flow of water through the retarding apparatus for operating the alarm; and my invention has for its object to prevent the operation of the alarm proper by small intermittent flows of water due to other causes than fire and which do not require an alarm to be given. To this end the invention may be said briefly to consist of a retarding apparatus including retarding and accumulating chambers having inlet and discharge ports and the ports of the retarding chamber having means for maintaining the inlet port closed and adapted to close the outlet port when the inlet port is open and vice versa for the purpose of insuring an accumulation of water in the chamber when an alarm is sounded, and provided with a rapid discharge from the chamber of any water admitted thereto intermittently from other causes than fire. Another feature of the invention is the particular construction of the inlet ports to the apparatus and from the retarding to the accumulating chamber, the former being, for the purpose of my invention, of the diminutive bore type, the object being in the case of this port to increase the velocity of the water passing therethrough and convert the flowing body into a jet of sufficient force to operate the controlling means; the ports effecting communication between the chambers having a comparatively large bore solely for retarding the flow.

For full comprehension, however, of my invention, reference must be had to the accompanying drawings in which similar ref-

erence characters indicate the same parts, 55 and wherein:

Figure 1 is a vertical sectional view of a retarding chamber; and

Fig. 2 is a transverse sectional view taken on line 2—2 Fig. 1. 60

The fire extinguishing and alarm system to which this invention has particular reference and the working of which is rendered more efficient by this invention, is disclosed in my companion application for patent 65 filed on the 17th day of September, 1917. The application of this retarding chamber is illustrated in the application just mentioned.

My present invention comprises a dual 70 chamber one portion 2 of which has a retarding function and the other, 3, acts as an accumulator. A single casting preferably embodies the accumulating and approximately half of the retarding chamber, the 75 other half of the latter consisting of a casting composed of a member 4 of the wall of the casting and an oblique partition 5 inclosing the chamber sub-divided by a wall 6 into inlet and outlet sub-chambers 7 and 8, 80 respectively. The inlet chamber 7 has the inlet pipe connected thereto by a tail-piece 12 clamped in place by a coupling 13 serving as a retaining means for a strainer 14. The opposite end of the inlet pipe is connected to the main valve chamber such as disclosed in my patent application above-mentioned in which the valve opens and water is allowed to flow into the inlet chamber 7 when pressure within the main valve 85 chamber becomes less than the pressure in the supply pipe. The discharge from the inlet chamber is of diminutive capacity presented by a plug 15 screwed into a tapped hole 16 in partition 5 and having a port 18 there-through of diminutively small bore, concavities 9 and 10 respectively, on opposite sides of the plug converging in the jet opening; the strainer being for the purpose of preventing sediment in the water of the system from 90 blocking this port 18. The outer side of this plug or bushing relatively to the inlet chamber 7 has an annular shoulder 19 encircling the port 18 and has a narrow top to facilitate the seating of one of the alternating 95 valves. The outlet from chamber 2 to the outlet sub-chamber 8 is through a relatively large port 20 and a correspondingly large 100 105

port 21 acts as a discharge from this sub-chamber 8 to a waste pipe or the like.

The partition between the ports 18 and 20 has a post 22 upon which a lever is fulcrumed between its ends as at 23 such ends being of different lengths, the short end extending over port 20 and carrying a valve 24 and the long arm extending over port 18 and being counter-weighted as at 25 and carrying a valve 26. This casting is detachably fastened in place upon the main casting by bolts 27 and nuts 28. The accumulating chamber is preferably located above the retarding chamber and communication is effected between them through a bushing 32 screwed into an opening 33 in an upwardly concaved partition 34 separating this chamber from the retarding chamber. This bushing has a relatively small central port 35 and concavities 30 and 31 in its opposite sides and converging in the port 35 thus imparting a jet-producing function to the bushing; and a series of fingers 36 supporting a downwardly concaved baffle-plate 37 the purpose of which is to check the water flowing from the accumulating chamber and prevent it from being projected from port 35 through the outlet port 38 in the top of this accumulating chamber.

30 Operation.

In the operation of apparatus of this type, the sole aim is to give alarm when fire occurs in a building protected by a fire-extinguishing system of the type to which this invention relates. These alarms are given when the sprinkler system or any portion of it is set in operation, and it is most desirable that no alarm be given unless the 40 sprinkler system is actually put into operation, which, with proper installation, invariably takes place in the event of fire. These alarms are actuated by apparatus operated in turn by the flow of water toward 45 the sprinkler.

It is important to prevent the operation of the alarm apparatus when the alarm valve is only intermittently momentarily opened without cause necessitating an alarm, 50 or in other words, until there is a steady continuous flow to the sprinklers, in which event the water discharged into the alarm pipe from the other part of the system enters and floods intake chamber 7 through port 18 thus raising valve 26 and closing valve 24, flooding chambers 2 and 3 and reaching port 38 which results in actuating the alarm.

Should water hammer occur the successive 60 impulses will cause comparatively small spurts of water to be conducted to chamber 7 and each impulse will intermittently lift valve 26 from its seat and the water will enter chamber 2, but during the 65 intermission between the impulses the

counter weight 25 will shut valve 26 and lift up valve 24 thus opening the relatively large port 20, and however rapid the impulses may be the relatively greater capacity of the port 20 will drain off this intermittently flowing water and prevent sufficient accumulation thereof to reach port 38. In this manner the operation of the alarm sounding or indicating apparatus is prevented when no cause exists for an alarm.

The plug 15 has a dual purpose in that it serves to concentrate the flow and thereby increase the velocity sufficiently to overcome the counter-weight 25 and displace the valve at the same time the flow is retarded. The 80 port 35 serves solely as a retarder; while the concaved partition 34 proportionately increases the capacity of the accumulating chamber.

What I claim is as follows:

1. A retarding chamber for automatic fire extinguishing and alarm systems consisting of a casing having a detachable portion, said portion having inlet and discharge sub-chambers therein and inlet and discharge ports respectively communicating with the inlet and discharge sub-chambers, a lever fulcrumed between its ends between the said ports and coöperating alternating check valves controlling said ports, said valves being carried by the opposite ends of said lever.

2. A retarding chamber for automatic fire extinguishing and alarm systems consisting of a casing having a detachable portion, said portion having inlet and discharge sub-chambers therein and inlet and discharge ports respectively communicating with the inlet and discharge sub-chambers, a lever fulcrumed between its ends between the said 100 ports and coöperating alternating check valves controlling said ports, said valves being carried by the opposite ends of said lever, one end of the said lever being longer than the other end and counter-weighted.

3. In a retarding apparatus of the type described including a casing, a partition extending obliquely across and dividing the interior of the casing into two chambers, one of said chambers constituting an accumulating chamber, a second partition subdividing the other of said chambers into inlet and discharge sub-chambers, said first mentioned partition having inlet and discharge ports, one of said ports being of diminutive bore and effecting communication between the inlet and accumulating chambers and the other of said ports being of comparatively large bore and effecting communication between said accumulating and discharge chambers and coöperating alternating check valves controlling said ports.

4. In a retarding apparatus of the type described including a casing, a partition extending obliquely across and dividing the

interior of the casing into two chambers, one of said chambers constituting an accumulating chamber, a second partition subdividing the other of said chambers into 5 inlet and discharge sub-chambers, said first mentioned partition having inlet and discharge ports, one of said ports being of diminutive bore and effecting communication between the inlet and accumulating chambers and the other of said ports being of 10 comparatively large bore and effecting communication between said accumulating and discharge chambers and a lever fulcrumed between its ends between said ports, one end

of the said lever being longer than the other 15 end and counter-weighted, and coöperating alternating check valves controlling said ports, said valves being carried by the opposite ends of said lever and the valve controlling the inlet port having a concave and relatively wide impact surface. 20

In testimony whereof I have signed my name to this specification in the presence of two witnesses.

JOHN R. MEADOWCROFT.
